UNITED STATES PATENT OFFICE.

CLARENCE D. PLATT, OF BRIDGEPORT, CONNECTICUT.

DESIGN FOR AN ELECTRIC-SWITCH HANDLE.

53,401.

Specification for Design.

Patented June 3, 1919.

Application filed March 8, 1919. Serial No. 281,541. Term of patent 14 years.

To all whom it may concern:

Be it known that I, CLARENCE D. PLATT, a citizen of the United States of America, residing at Bridgeport, Conn., have invented a new, original, and ornamental Design for an Electric-Switch Handle, of which the following is a specification.

In said drawing:—

Figure 1, is a perspective view of a han-

dle embodying the ornamental design of my invention.

Fig. 2, is an end view.

Fig. 3, is a sectional view showing the concave shape of the finger piece.

I claim:—

The ornamental design for an electric switch handle substantially as shown.

CLARENCE D. PLATT.
